UNITED STATES PATENT OFFICE.

EMERY CORMIER, OF NASHUA, NEW HAMPSHIRE.

TEMPLE SELVAGE TRIMMER.

Application filed July 30, 1923. Serial No. 654,528.

To all whom it may concern:

Be it known that I, EMERY CORMIER, a subject of the King of Great Britain, residing at Nashua, in the county of Hillsboro⁵ and State of New Hampshire, have invented certain new and useful Improvements in Temple Selvage Trimmers, of which the following is a specification.

This invention relates to improvements in box looms, and more particularly to the provision in that type of loom of a temple selvage trimmer at the box end of the loom.

In weaving cloth on a box loom the weft or filling thread running to the shuttle carrying the bobbin of the color not in use, is drawn forwardly by the advancing cloth and lies along the edge of the selvage while the weaving is continued by filling threads of another color from the other shuttle or shuttles according as there are two or more colors in the cloth. The formation of this extra and undesirable thread parallel to the selvage edge continues until the time comes to again use the idle shuttle, when this thread is again picked through the shed. This forms extra loops of the yarn forming the weft thread alternating in color, when the cloth is being woven from two colors only, all along the selvage at the box end of the loom. If more than two colors are used the threads will overlap and form loops of two or more threads. These loops are secured at each end to the cloth and heretofore they have been drawn so tight against the selvage, by the operation of the shuttle and the beat up of the lay, that great difficulty has been experienced in trimming them from the selvage. So far as I am aware the expensive hand trimming has been the universal commercial practice in the mill, prior to my invention.

Trimming these selvage loops of the varicolored weft threads by hand is not only expensive but is a slow and tedious operation. Accordingly the object of the present invention is to provide a trimmer, operated by the loom itself, for severing these loops of extra thread at the box end of the selvage while the cloth is being woven in the loom. I believe that I am the first to provide a box-loom with an automatically operated selvage trimmer which will effectually sever the filling thread loops from the selvage without injuring the cloth.

While the portions of the weft threads left attached to the selvage at the box end of the

loom have been described as selvage "loops" because most frequently attached to the selvage by both ends, it will be understood that when weaving cloth in stripes from two or more colors the formation of complete loops from the inactive filling threads depends upon the character or design of the cloth being woven. The inactive filling threads may, according to the nature of the design being woven and the positions of the temple and the trimmer relative to the characteristic features of said design, be attached to the selvage at one end only at the time the automatic trimmer becomes operative. In its broader aspects the object of the present invention is to provide means in a box loom for severing all surplus filling threads, of whatever nature they may be, from the box end selvage before the cloth leaves the loom. The term "loops" in the appended claims should be so construed where not otherwise limited.

To the accomplishment of this object and such others as may hereinafter appear, as will readily be understood by those skilled in the art, the invention comprises the features and combinations of parts hereinafter described and then particularly pointed out in the appended claims.

The various features of the invention will best be understood from a description of the preferred embodiment thereof illustrated in the accompanying drawings, in which:

Figure 1 is a view, in perspective, of the selvage trimmer constructed and arranged to be operated by the forward movement of the temple at the box end of the loom at each beat up of the lay, a portion of a two color blanket being shown in the process of being woven,

Fig. 2 is a view, in front elevation, of the selvage trimmer as shown by Fig. 1,

Fig. 3 is a cross-sectional view, in elevation, of the operating mechanism taken on the dot and dash line of Fig. 2 and looking in the direction of the arrows 3-3 thereon,

Fig. 4 is a cross-sectional view, in elevation, of the trimming mechanism taken on the dot and dash line of Fig. 2 and looking in the direction of the arrows 4-4 thereon, and

Fig. 5 is a diagrammatic view, in plan, of the outer end of the temple head illustrating the manner of forming a slack loop from the filling thread leading to the idle shuttle when that shuttle is again brought into posi-

tion for the first pick through the shed upon a change of color.

The invention, as has already been pointed out, is for use on a box loom, of any well-known type, for example a Crompton & Knowles box loom, and is applied to the temple at the box end of such a loom, because the filling thread loops to be trimmed by the mechanism of this invention are formed only on the selvage at the box end. Since the invention is not concerned with a particular form or construction of loom no detailed description or illustration of the loom itself is necessary.

15 Looms are universally provided with a temple at each side, the main function of which is to maintain the cloth forward of the fell in a stretched condition of uniform width. In the embodiment of the invention illustrated in the drawings the temple selvage trimmer is combined with the box end temple 10 (Fig. 1), the temple stand 12 of which is adjustably mounted on the breast beam of the loom by bolts threaded 20 in the customary manner into the upright portion 14 of the usual supporting bracket 15, which in turn is bolted to the breast beam. The temple thus projects rearwardly from the breast beam and its shank 16 slides in 25 the stand 12 and is yieldingly normally projected rearwardly by a spring (not shown) in the temple stand. This shank 16 carries at its rearward end the temple head 10. Within the temple head, which is slotted to 30 permit the passage of the cloth, there is provided the usual pin pointed or "porcupine" temple roll (hidden from view in Fig. 1). At each beat up of the lay the front of the lay strikes against a depending heel 18 35 (Fig. 2) forcing the temple forwardly over the cloth. This latter feature is referred to because it is mounted on the temple head and is conveniently utilized in the present invention for operating the novel selvage trimming mechanism.

With this preliminary description of the pertinent features of the loom I may now pass to a description of the preferred form of construction of the present invention.

50 Secured to the lower face of the temple stand 12 is a table 20 which projects inward and lies in front of the temple head 10. This table is slotted at 22 (Figs. 1 and 4), for the reception of the vertically arranged 55 trimming knives, and at the inner edge of said slot there is provided a vertical bracket or stand 24 having a right-angular extension 26 running parallel to the temple head, beneath which and over the table 20 the cloth travels. The inner wall 25 (Fig. 2) 60 of the stand 24 acts as a gage for the selvage edge of the cloth. The cloth is held down upon the table 20 by means of a presser foot which comprises a plate 28 guided for vertical movement on the stand 24 (see Fig.

2) and yieldingly pressed down upon the cloth. To this end a pin 30 is guided for vertical movement in a U-shaped bracket 32, projecting inwardly from the stand 24, an expansion spring 34 being coiled on the pin and held thereon in the manner clearly shown by Fig. 2.

The knives for trimming the selvage loops, shown lying along the edges of the cloth illustrated in Fig. 1, are supported in a vertical slot 36 in the outer face of the stand 24. These comprise a fixed knife 38 seated in the bottom of the slot and a movable knife 40, also in the slot and overlying the fixed knife. The fixed knife 38 is slotted horizontally at its rear edge, just above the table 20 (Fig. 4), and provides an upwardly directed cutting blade 42 in the plane of the surface of the table. The movable knife 40 has an oblique lower edge which forms a downwardly directed cutting blade 44. The knives are held in the slot 36 by a cover plate 46. When the knife 40 is reciprocated, by mechanism presently to be described, the blade 44 shears across the blade 42 at each downward stroke, thus severing any filling thread attached to the selvage which has been brought to a position between the blades by the advance of the cloth. The cutting edges of the trimming knives are located about one-sixteenth of an inch from the selvage gage 25 thus insuring a sufficiently close trimming of the selvage loops but without damage to the selvage. It will be understood from Fig. 4 that the stand 24 is cut away behind the knives to permit a tracking of the looped filling threads into position between the cutting blades when open, as the cloth is advanced past the knives.

The mechanism for operating the reciprocating knife 40 will now be described. The proximate actuator for the knife 40 is a bell-crank 48 (Fig. 2), fulcrumed at 50 on the knife side of the stand 24, having its horizontal arm connected to the upper end of the knife bar by a pin and slot 52 and normally maintained raised by a suitably mounted spring 54. The limit of upward movement is determined by the engagement of the lower end of a vertical guide slot in the knife bar with a bolt 56 (see Fig. 4). A wear piece on the vertical arm of the bell-crank 48 is engaged by an arm 58 fixed on a rock-shaft 60 journaled in a bearing 61 at the forward edge of the table 20. When this shaft is rocked in a clockwise direction, viewing Fig. 4, the knife is depressed, a return being effected by the spring 54. The shaft 60 is rocked at each beat up of the lay by the mechanism shown in Fig. 3. The shaft carries a second fixed arm 62, substantially parallel to the arm 58, which underlies a rearwardly extending arm 64 loosely pivoted at its forward end on the temple stand and carrying a roll 66 at its 130

rear end. The temple stand is provided with additional guiding brackets 68 and 70 which receive an auxiliary slide 72 pinned to the temple shank at 74. The slide 72 carries a 5 cam block 76 (Figs. 1 and 3) which, at each forward movement of the temple shank 16, engages the roll 66 and thus, through the mechanism described, rocks the shaft 60 and depresses the knife 40 causing its blade 44 10 to make a shear cut across the blade 42 of the fixed knife 38. As the lay swings rearwardly the temple head springs rearwardly and the movable cutting blade moves to open position.

15 It is obvious that each filling thread selvage loop must be provided with sufficient slack to enable it to lie across the knife blades. Otherwise the knives could not sever the thread. The manner in which this 20 slack is formed is an extremely important feature of the invention and will be described in detail later. Assuming for the present that each loop is slack, as illustrated in Fig. 1, the means will now be described 25 for opening up the loops so that their ends attached to the selvage will be drawn outwardly and attain a position substantially normal to the selvage at the time they pass between the knife blades.

30 The rear end of the horizontal arm of the bell-crank 48 has a pin engaging in a slot (see Fig. 1) in the outer end of a lever 78 pivoted centrally on the rear face of the knife stand extension 26. The inner end of this lever 35 has pivoted thereto a depending pawl 80 adapted to engage the teeth of a ratchet 82 rotatable on a pin fitted in the face of said extension 26. The lever 78 is pressed down by a suitably mounted spring 84 engaging its inner end and the pawl is held to the ratchet 40 by a suitably connected coil spring 86. A lock pawl 90 is pressed toward the ratchet by a spring 92. With this construction the ratchet is rotated one step, in a counter-clockwise direction as seen in Fig. 1, at each 45 upward movement of the knife 40. This rotation is utilized to actuate a loop-spreader 94 in the following manner. The ratchet carries a crank pin 96 on which is pivoted a 50 loop-spreader arm 98 the longitudinal movement of which is guided by a screw 100 entering the stand extension 26 through a slot 102 in the inner end of the arm. The outer end of the arm 98 carries a loop spreading 55 foot 104 which may be of any suitable construction but is preferably formed of a plurality of independently yielding members, as clearly shown in Fig. 1. As the crank pin 96 traverses the lower portion of its orbit of 60 motion the loop spreading foot is advanced across the line of feed of the selvage of the cloth and the vertical position of the arm 98 is such, at this time, that the spreader feet engage and rub across the table 20 which 65 places their springs under some tension.

Thus as the loops are advanced they are periodically engaged by the spreading foot 104 during three or four successive advance steps thereof before the crank pin begins to rise and thus carry the foot upward and then rearward. This contact with the loops is sufficient to open each loop to its fullest extent just before reaching the trimming mechanism, and thus provide for an efficient trimming operation by the shearing action of 70 loop cutting knives 38 and 40. The loop *w* being fed to the knives, in Fig. 1, is shown as having just been stretched by the loop-spreader which is rising from its operative 75 loop spreading position.

The table adjacent the knives should be kept clear of the accumulation of thread ends and to this end a thread end clearer is provided. The clearer is in the form of a rotary blade 110 which turns in the space 80 between the knives and temple stand (see Fig. 1). The two or more blades of the clearer are of such length that they sweep across the table 20, engaging and ejecting all the severed thread ends that do not fall through the slot 22. The clearer is carried on the inner end of a horizontal shaft 112 journaled in a bearing 114 on the top of the temple stand. Between the clearer and the journal is a ratchet 116 adapted to be engaged by a pawl 118 carried on the auxiliary slide 72. Thus the clearer is rotated, step by step, at each beat up of the lay. A coiled shaft spring 120 holds the clearer yieldingly in its bearing. As shown by Figs. 1 and 3 90 the pawl 118 is held loosely on the slide 72 to prevent breakage in case of jamming.

I will now describe the important feature of providing slack in the selvage filling thread loops. Fig. 1 illustrates the 95 weaving of a two color blanket, the full line stripes indicating blue, for example, and the dotted line stripes white. As shown in Fig. 1 a blue stripe has just been completed and the picking of the white weft 100 threads for the adjoining white stripe has been started. The filling thread loops along the selvage are marked *b* and *w* to indicate blue or white threads, and the white loop just produced is shown by an irregular dotted line where it lies hidden within the temple slot. The thread *B* runs from the rear edge of the last blue stripe woven to the shuttle which carries the blue thread bobbin, which we will assume is in the upper box, now raised above the picker bar. The thread *W* runs to the shuttle which carries the white thread bobbin and is in the lower box, now in position to be picked 110 through the shed and weave a white stripe. 115 At the succeeding beat ups of the lay in weaving the white stripe the end of the blue thread *B* attached to the selvage is advanced with the cloth through the slot in the temple head 10 and, at the time the white 120

130

stripe is completed, lies in approximately the position of the dotted line B in Fig. 5, that is, behind a hook 130. It reaches its position behind the hook in the following manner. The hook is on the rear end of a lever, pivoted at 132 on the temple head, (Fig. 3) having a weighted forward end 134 which normally maintains the hook projected upwardly through a housing 136 at the rear edge of the temple head. It thus stands normally across the temple head slot but beyond the outer end of the temple roll. At each beat up of the lay a projection thereon (not shown) engages and lifts the hook end 134. This lowers the hook into its housing 136. Before the completed blue stripe has passed completely into the temple slot the threads B runs from the selvage to the idle shuttle in front of the hook 130. But since the hook is depressed at each beat up of the lay this idle thread B can be freely advanced with the cloth and soon reaches a position where the hook, when it rises, on the retreat of the lay, comes up at the rear of the thread. This stage of the formation of the slack in the selvage loops is illustrated in Fig. 1. As the thread B is drawn forward by the advance of the cloth it passes under a spring pressed presser foot 138 (see Figs. 3 and 5) located on the temple head just in advance of the hook 130. This presser foot is guided by a stem 140, and serves to maintain the idle thread taut, as is shown by the dotted line B in Fig. 5. Now, when the blue color is to be used again, its shuttle box is brought down into weaving position and at the first pick of the blue thread through the shed it is drawn taut around the hook 130, as shown by the full line B in Fig. 5. Thus the hook prevents the blue thread, at this first pick, from being drawn tightly to the selvage as is the present practice, but on the other hand insures the formation of the slack loop illustrated in Fig. 5. The next beat up of the lay withdraws the hook from the loop so that it may advance freely with the cloth. The slack thus produced is utilized in severing the loops in the manner hereinbefore described. It will, of course, be understood that at each succeeding pick the blue thread is drawn in tightly to the selvage and the hook does not again produce slack until the first pick of the white thread after the blue stripe has been completed.

It becomes necessary, at times, to pick out a portion of the weft threads by hand, because of some imperfection or for other reasons, and at such times the temple head must be held in its forward position. To provide for this the temple shank 16 is provided intermediate its ends with a bore 150 (Fig. 2), and a sliding locking-pin 152 having a head 154 is carried in a horizontal housing 156 on the forward end of the tem-

ple stand. On moving the temple head forward, by hand, to a position where the bore 150 registers with the pin 152, the pin can be shot into the bore and thus lock the temple head against return movement until it is desired to again continue the weaving operation, when the pin 150 is withdrawn.

Those familiar with the art of weaving blankets and the like, having striped end borders or woven throughout with different colored stripes of the same or varying width according to the character of the design, will understand that the formation of complete box end selvage loops depends upon whether the width of any stripe or portion of one color, is less than the distance from the fell to the trimming device located forward thereof. As illustrated, a striped blanket is being produced of a design permitting five alternating white and blue stripes to be woven before the first of these five stripes is brought to the trimmer by the advance of the cloth through the loom. Accordingly the box changing mechanism operates five times and produces five complete loops from the inactive filling threads before the first of these loops is severed. A complete loop, i. e., attached to the selvage by both ends, will be formed at each box changing operation provided the width of the stripe just woven is less than the distance from the fell to the trimming device.

Assuming now that a blanket is being woven of such design that the stripes are wider than the distance from the fell to the trimming device then the advance of the cloth will bring the forward, selvage-attached end of the loop to the trimming device before a box changing operation occurs and while the rear end of the loop still is on the bobbin in the idle shuttle. This condition would also occur when a blanket is being woven having a border of varicolored stripes and a central, or main portion of one color. In weaving such a design the inactive filling thread forming the last-woven colored border-stripe would, in the absence of a trimming device, continue to be drawn from the bobbin of the idle shuttle during the whole of the weaving of the long central portion of the blanket. This bobbin loop-end would not be attached to the selvage until the next box changing operation to start weaving the succeeding border portion.

The present invention provides for severing the forward or selvage-attached end of all inactive filling threads that if left unsevered eventually would form complete loops across portions of the cloth of one color wider than the distance from the fell to the trimming knives 38—40, resulting in a considerable saving of the weft thread yarn and keeping the selvage clear of said inactive threads. The presser foot 138 is of

70

130

great importance in this connection. Its yielding pressure on the inactive thread holds the portion thereof forward of the foot in a taut condition but still permitting it to be drawn from the bobbin of the idle shuttle while the forward movement of the cloth is advancing the selvage-attached end to the trimmer. Its yielding pressure also permits the spreader 94 to effectually function to draw said attached end normal to the selvage edge in the same manner as described for the shorter selvage loops. After severance of the forward end of such a loop no more thread is drawn from the bobbin of the idle shuttle until the next box changing operation, the severed inactive thread from that bobbin remaining under control of the presser foot 138 until it again becomes active. After the boxes are changed the loose end produced by the previous trimming operation, and now attached to the selvage, is advanced with the cloth, acted on by the spreader 94 and finally severed. In practice the trimmer may conveniently be about six or seven inches forward of the temple so that the loose end would approximate that length and any excess of the width of the stripe thereover will be a clear saving of filling thread yarn.

It will be understood from the foregoing description that my novel spreader 94 will function to extend, for proper presentation to the trimmer, any loose thread ends attached to the box end selvage however they may have been formed, causing the loom to produce cloth requiring no further trimming of that selvage edge. Furthermore, since the selvage gage 25 maintains the selvage gage 25 maintains the selvage edge spaced from the field of operation of the cutters, all danger of injuring the cloth at any filling thread trimming operation is wholly eliminated.

That my temple selvage trimmer is accurate and efficient in operation will be apparent from the foregoing description. Cutting mechanism in a vertical plane cannot be employed, without danger of injury to the cloth, unless means is provided to produce slack in the selvage loops, and those skilled in the art will recognize that it is not possible to trim these loops, when tight, with a knife operating in the plane of the cloth. The movement of the movable cutting blade may be effected from any moving part of the loom, and the invention is not limited to a control from the temple.

While the novel features of the invention are best adapted for use in a box loom, those skilled in the art will recognize that some features described are useful in other kinds of looms. The various features of my invention, therefore, are not limited to use in combination with each other, or to use in a box loom, wherever it is clear that the ad-

vantages claimed for the invention may be obtained from other combinations or other applications of its underlying principles.

It will be clear to those skilled in the textile art, and with the general objects of the present invention in view, that changes may be made in the details of structure, the described and illustrated embodiment of the invention being intended as an exploitation of its underlying essentials, the features whereof are definitely stated in their true scope in the claims herewith.

That which is claimed as new, is:—

1. In a box loom, mechanism forward of the temple at the box end of the loom for severing the successive selvage loops being formed by the filling threads leading to the bobbin of an idle shuttle while an active shuttle from another box is being picked through the shed, means for producing slack in each loop during its formation, each loop, when completed, lying along the selvage across the stripe formed by the weft threads picked by said active shuttle and having its ends secured to the selvage at each margin of said stripe, and means for operating said mechanism controlled by the movement of the temple to advance the cloth being woven.

2. In a box loom, mechanism forward of the temple at the box end of the loom for severing the successive selvage loops being formed by the filling threads leading to the bobbin of an idle shuttle while an active shuttle from another box is being picked through the shed, means for producing slack in each loop during its formation, each loop, when completed, lying along the selvage across the stripe formed by the weft threads picked by said active shuttle and having its ends secured to the selvage at each margin of said stripe, said mechanism comprising a fixed and a movable knife, mechanism for operating said movable knife, and actuating means for said operating mechanism mounted on the temple.

3. In a box loom, means for producing a slack filling-thread-loop, a loop severing mechanism forward of the temple at the box end of the loom comprising a cutting blade movable across the selvage edge in a plane normal to the face of the cloth, and mechanism for operating said cutting blade by or through each beat up of the lay.

4. In a box loom, means for producing a slack filling-thread-loop, a loop cutting mechanism supported from the frame at the box end of the loom with its field of action at the selvage edge forward of the fell and operating in a vertical plane, and means for operating said cutting mechanism from a moving part of the loom.

5. In a box loom, filling-thread-loop cutting mechanism supported from the frame with its field of action at the selvage edge forward of the fell comprising shear blades,

- in a vertical plane, constructed and arranged to receive a filling-thread-loop between them as the cloth is advanced, a selvage gage in fixed position relative to the path of movement of the cloth for directing the loops to said blades, and means for operating said cutting mechanism from a moving part of the loom.
6. In a box loom, means for producing a slack filling-thread-loop, a loop cutting mechanism supported from the frame with its field of action at the selvage edge forward of the fell and operating in a vertical plane, a table at the rear of said cutting mechanism to support said slack loops in a horizontal plane as they are advanced into position to be cut, and means for operating said cutting mechanism from a moving part of the loom.
- 10 7. In a box loom, filling-thread-loop cutting mechanism supported from the frame with its field of action at the selvage edge forward of the fell and operating in a vertical plane, means independent of the cutting mechanism for insuring that the loop ends are placed within the field of action of said cutting mechanism as the cloth is advanced, and means for operating said cutting mechanism from a moving part of the loom.
- 15 8. In a box loom, automatically operating means adjacent the fell for forming slack filling-thread-loops on the box end selvage of the cloth, an automatically operated loop cutting blade forward of the fell, means for advancing the cloth to bring said slack loops to the cutter, and means operating on the cloth while it is being advanced to insure that the selvage ends of said loops are presented transversely to said blade prior to 30 its operation thereon.
- 35 9. In a box loom, a filling-thread-loop severing mechanism operating at the selvage edge forward of the fell, means for operating said mechanism from a moving part of the loom, means for directing the selvage edge past said cutting mechanism, and means for increasing the normal size of each loop and then spreading said enlarged loops prior to the operation of said severing mechanism thereon whereby said loops may be 40 severed without damage to the cloth.
- 45 10. In a box loom, means for producing slack in the selvage filling-thread-loops while, being formed during the weaving, 55 and means operated by the loom for severing said slack loops from the selvage.
- 60 11. In a box loom, means for producing slack in the selvage filling-thread-loops, means for spreading said slack loops, and means operated by the loom for trimming said loops after they have been spread.
- 65 12. In a box loom, means for producing slack in the selvage filling-thread-loops, means for spreading said slack loops, means for trimming the spread loops, and common

actuating mechanism for said spreading and trimming means.

13. In a box loom, means for producing slack in the selvage filling-thread-loops, devices movable across the path of advance 70 of the cloth for spreading and then trimming said slack loops, and means controlled by the advance of the cloth for operating said devices.

14. In a box loom, means for producing slack in the selvage filling-thread-loops, devices movable across the path of advance of the cloth, but in different planes, for spreading and then trimming said slack loops, and means controlled by the advance 80 of the cloth for operating said devices.

15. In a box-loom, means for producing slack in the selvage filling-thread-loops, a loop cutter movable in a plane normal to the cloth, a loop spreading device movable 85 in the plane of the cloth, said device being in advance of the cutter in the path of feed of the cloth through the loom, and means for operating said cutter and device.

16. In a box-loom, means for producing slack in the selvage filling-thread-loops, a loop cutter movable in a plane normal to the cloth, a loop spreading device movable in the plane of the cloth, said device being in advance of the cutter in the path of feed 90 of the cloth through the loom, and means for simultaneously operating said cutter and device.

17. In a box-loom, means for producing slack in the selvage filling-thread-loops, a loop cutter movable in a plane normal to the cloth, a loop spreading device movable in the plane of the cloth, said device being in advance of the cutter in the path of feed 100 of the cloth through the loom, and means controlled by or through the beat up of the lay for effecting an operative movement of said cutter and device after each pick of the loom.

18. In a box loom, means for producing slack in the selvage filling-thread-loops, a loop trimming cutter, a loop spreader movable step-by-step in a fixed path, and means for advancing said spreader one step in its path at each operation of the loop cutter. 110

19. In a box loom, means for producing slack in the selvage filling-thread-loops, a loop trimming cutter, a loop spreader having a yieldingly mounted loop engaging foot, and means for moving said foot across the 120 path of feed of the loops and in the plane thereof prior to an engagement of said loops with said trimming cutter.

20. In a box loom, means for producing slack in the selvage filling-thread-loops, a loop trimming cutter in a vertical plane at the selvage edge, and means in advance of said cutter in the path of feed of the cloth for placing the loop ends in a position generally transverse to said cutter. 125

21. In a box loom, means for producing slack in the selvage filling-thread-loops, a cutter for severing said loops during the advance of the cloth, and means for spreading said loops for the operation of said cutter thereon. 70
22. In a box loom, a filling-thread-loop severing mechanism forward of the temple at the box end of the loom, and means for clearing from the loom the thread ends formed by the loop severing operation. 75
23. In a box loom, a filling-thread-loop severing mechanism forward of the temple at the box end of the loom, and means for clearing from the loom the thread ends formed by the loop severing operation, said severing mechanism and clearer being operated from a moving part of the loom. 80
24. In a box loom, a filling-thread-loop severing mechanism forward of the temple at the box end of the loom, and means for clearing from the loom the thread ends formed by the loop severing operation, comprising a rotary blade adjacent the severing mechanism and rotated by or through the beat up of the lay. 85
25. In a box loom, a mechanism forward of the temple at the box end of the loom for severing the successive selvage loops being formed by the filling threads leading to the bobbin of an idle shuttle while an active shuttle from another box is being picked through the shed, the thread forming each loop lying along the selvage and across the stripe formed by the weft threads picked by said active shuttle, means for producing slack in said loops during their formation, means for operating said severing mechanism and for advancing the cloth being woven and said loops past said mechanism, and means for drawing the loop ends outwardly from the selvage edge in the plane of the cloth for the action of said severing mechanism thereon, as said ends are successively presented to the severing mechanism by the advance of the cloth. 90
26. A loom comprising a frame, filling thread cutting mechanism supported from the frame, a table adjacent said cutting mechanism, and means for sweeping the cut threads from said table while the loom is in operation. 105
27. A loom comprising a frame, filling thread cutting mechanism supported from the frame, a thread end clearer, operating means for said cutting mechanism and said clearer, and actuating devices for said means mounted on the temple slide. 110
28. In a loom of the type having means for picking a shuttle, with a bobbin of one color, through the shed and box changing mechanism to bring a shuttle with a bobbin of another color into the field of operation of said pick, means for preventing the thread from said second shuttle from being drawn taut to the selvage on the first pick only from the box of said second shuttle through the shed, said means being thereafter inoperative until the boxes are again changed. 115
29. In a box loom, temples, and means adjacent the temple at the box end for engaging the filling thread on the first pick only after a change of color and holding it away from the selvage, and means for thereafter releasing said thread, whereby on succeeding picks of that color the weft threads are drawn taut to the selvage. 120
30. In a box loom, temples, and means adjacent the temple at the box end for engaging the filling thread on the first pick only after a change of color and holding it away from the selvage, and means operated by or through the beat up of the lay for releasing said thread, whereby on succeeding picks of that color the weft threads are drawn taut to the selvage. 125
31. In a loom of the type having box changing mechanism, a plurality of shuttles carrying bobbins of distinctive colors, and the usual lay operated temples, means for holding taut the thread or threads to the idle shuttle or shuttles during the weaving of a stripe by the remaining shuttle thread, and means for producing a slack in the selvage loop at the box end of the loom at the first pick only when the boxes are changed to weave a stripe of another color. 130
32. In a loom of the type having box changing mechanism, a plurality of shuttles carrying bobbins of distinctive colors, and the usual lay operated temples, a device mounted adjacent the temple at the box end and forward of the run of the shuttle through the shed for engaging the filling thread running to the idle shuttle in the box which is not in picking position and holding it away from the selvage to produce slack in the selvage loop at the first pick when the boxes are changed and the idle shuttle is employed to continue the weaving, and means for releasing the thread from said device after said first pick by that shuttle whereby on succeeding picks thereof the thread passing to the rear of said device is unengaged thereby and a tight selvage is produced. 135
33. In a loom of the type having box changing mechanism, a plurality of shuttles carrying bobbins of distinctive colors, and the usual lay operated temples, a housing on the box end temple outside the temple roll, a hook in said housing normally blocking the temple slot, and means for housing said hook at each beat up of the lay, whereby the thread running to the shuttle not in use will eventually be placed in advance of said hook by the advance of the cloth through the loom. 140
34. In a loom of the type having box changing mechanism, a plurality of shuttles carrying bobbins of distinctive colors, and 130

the usual lay operated temples, a lever fulcrumed in the box end temple outside the temple roll having a hooked rear end, means for holding said hook normally extending 5 across the temple slot, and means operating at each beat up of the lay for depressing said hook below said slot, whereby the idle thread may advance to the forward side of said hook and be caught and held thereby on the first 10 pick of the shuttle carrying said thread when the boxes are changed.

35. In a box loom, temples, a yielding presser foot within the slot of the box end temple and outside the temple roll, a hook 15 opposite said presser foot blocking the rear side of said temple slot, means for maintaining the hook normally in said position, and means for periodically withdrawing the hook to free the temple slot of said obstruction.

36. In a box loom, temples, a yielding presser foot within the slot of the box end temple and outside the temple roll, a hook at the rear face of the temple opposite said presser foot, means for maintaining the hook 25 in said position while a shuttle is picked through the shed, and means for withdrawing said hook at each beat up of the lay.

37. In a box loom, box changing mechanism to produce stripes of different character, 30 means for forming a filling-thread-loop extending wholly across each stripe on the selvage at the box end, and means for producing slack in said loops.

38. In a box loom, box changing mechanism to produce adjacent stripes having different characteristics, means for forming a 35 waste filling thread of one characteristic extending from the box end selvage of an adjacent weft stripe of another characteristic, and thence to an idle shuttle means for severing said waste thread from the selvage, and means for holding the loose end thus 40 formed to enable the weft to be drawn in when the box carrying the idle shuttle repeats.

39. In a box loom of the type having box changing and cloth advancing mechanism, temples, a presser foot within the slot of the box end temple and in the path of the filling 50 thread running from the selvage to the bobbin of an idle shuttle, means for causing said presser foot yieldingly to clamp said filling thread whereby the run of said thread from its attachment to the selvage to said presser 55 foot is held taut but is permitted to draw from its bobbin as the cloth is advanced, and automatic means for severing said filling thread before the cloth leaves the loom.

40. In a box loom of the type having box 60 changing and cloth advancing mechanism, temples, a yielding presser foot adjacent the selvage and outside the temple roll of the box end temple adapted to bear upon the filling thread running to the cloth from an 65 idle shuttle, and filling thread severing

means located in the path of said advancing thread and operated by the loom.

41. In a box loom of the type having box changing and cloth advancing mechanism, temples, a yielding presser foot adjacent the 70 selvage and outside the temple roll of the box end temple adapted to hold all inactive filling threads away from the selvage while another filling thread is being picked through the shed, and a cutter forward of the temple operating successively upon said threads as they are advanced by the moving cloth.

42. In a box loom, temples, and a yielding presser foot outside the temple roll of the 80 box end temple operating automatically to continuously press upon and hold in inactive position all filling threads, that are attached to the selvage at one end, which are not being used to weave additional cloth.

43. In a box loom of the type adapted 85 to produce adjacent stripes having different characteristics, a filling thread cutter forward of the temple at the box end of the loom, a yielding presser foot adjacent said temple for holding taut, during the continued weaving of a stripe wider than the distance from the temple to the cutting means, all filling threads extending from the selvage to the bobbins of idle shuttles, and means for operating said cutter to sever 90 said threads from the cloth while still connected to said bobbins.

44. In a box loom, means at the box end 100 of the loom for holding waste filling threads in substantially the plane of the cloth, a device movable to draw the end portions of said threads outwardly from the selvage across said means into a position generally normal to the selvage edge, a cutter, and means for feeding said threads from said device and past the cutter to be severed thereby.

45. In a box loom, a hook outside the 110 selvage at the box end and opposite the fell but in advance of the path of active shuttles through the shed, means for withdrawing said hook after a change of color to permit the just active but now idle filling thread to pass from its rear side to its forward side, and means for maintaining said hook in operative position on the first pick of said filling thread when its shuttle again becomes active, whereby the hook prevents said thread on said first pick after each change of color 115 from being drawn taut to the selvage and produces a slack selvage loop.

46. In a box loom, automatic means for 120 increasing the length of the filling thread which is to form a loop on the box end selvage and extending from a stripe of one color across the intervening cloth to the next stripe of the same color, and automatic means for severing said loop from the selvage.

47. In a box loom, temples, temple operating means, and means operated automatically by the movement of the temples for producing slack in the filling thread loops formed by the box changing operation, for spreading said slack loops, and for severing said spread loops.
48. In a box loom, means adjacent the fell at the box end of the loom for engaging the filling thread leading to an idle shuttle and forming a slack selvage loop on the first pick when said shuttle becomes active whereupon said means becomes inoperative until the next box changing operation, and means forward of the fell for severing said slack loops.
49. In a box loom, a member mounted on the temple at the box end of the loom, outside the edge of the cloth but inside the filling thread leading to an idle shuttle, adapted to be engaged by said thread on the first pick when said shuttle becomes active whereby to form a slack selvage loop, means to release said loop from said member before the next succeeding pick of said shuttle, and means for severing said slack loop from the selvage.
50. In a box loom, means at the fell for producing slack in the filling thread loops attached to the box end selvage, means forward of the fell for severing said loops, and actuating means therefor controlled by the operation of the loom.

EMERY CORMIER.
